SPARK PLUG

Paul G. Andres, Oak Park, Ill., assignor to Bowes
Seal Fast Corporation, Indianapolis, Ind., a
corporation of Indiana

Application July 1, 1940, Serial No. 343,330

2 Claims. (Cl. 123—169)

This invention relates to spark plugs commonly employed in gas engines and has for its primary object the provision of a shield about the central insulating porcelain to not only increase the dielectric path thereover but also to serve as a resilient cushion to prevent breakage of the porcelain particularly when the plug is being installed or removed as frequently happens when the spark plug wrench slips and strikes the porcelain.

A further primary object of the invention is to provide a sealing structure cooperating with the insulating shell to aid in forming a shell retaining means and further, to prevent unwarranted disassembling of the plug.

These and other objects and advantages of the invention will become apparent to those versed in the art in the following description of one particular form of the invention as illustrated in the accompanying drawing, in which

Fig. 1 is a side elevation of a plug embodying the invention;

Fig. 2, a top plan view;

Fig. 3, a central vertical section on the line 3—3 in Fig. 2; and

Fig. 4, a transverse section on the line 4—4 in Fig. 3.

Like characters of reference indicate like parts in the several views in the drawing.

A metallic body 10 is formed in the usual manner to have a central bore therethrough provided with an annular shoulder 11 on which is seated an insulating gasket 12 preferably of a heat conducting type. The usual porcelain 13 is provided with a reduced diameter nose 14 which extends below the shoulder 11 in spaced relation from the wall of the bore through the body 10 to carry the central electrode 15 and present its lower end centrally of the lower opening into the body 10. The porcelain 13 has a larger diameter portion above the nose 14 to extend over and seat on the gasket 12. The porcelain extends upwardly a short distance by this larger diameter and then is reduced in diameter to form a shoulder 16 within the bore of the body 10 and the porcelain extends upwardly therebeyond to project from the body 10 in the usual manner.

A ferrule 17 is screw-threadedly engaged with the wall of the bore in the body 10 and is screwed down against an annular gasket 18 to complete the seal of the porcelain 13 in the body 10. This ferrule 17 when screwed down has its top end spaced slightly below the top end of the body 10, as indicated in Fig. 3. In order to turn the ferrule 17, it is provided with one or more slots 19, herein shown as two in number, across its upper

end so that a spanner wrench or the like may be employed to tighten or loosen the ferrule. By so forming the ferrule, there is no upper projecting part of this member as is the usual case where the seal is completed by a screw-threaded member. This prevents tampering with the plug and requires that a person equipped with the proper wrench be consulted to disassemble the porcelain from the body. The body 10 is thus to be seen as forming an annular flange 20 extending above the top end of the ferrule 17 spaced outwardly from the porcelain 13.

An insulating shell 21 is formed to be generally cylindrical and open at its lower end to telescope over the upper exposed part of the porcelain 13 and have the lower end of the shell 21 fit within the flange 20 and rest by its lower end against the top end of the ferrule 17. The upper end of the shell 21 fits over the top end of the porcelain 13 and has a central opening therethrough fitting around the periphery of a washer 22, the washer 22 serving as means for centering the shell 21 about the porcelain. The length of this shell is made to be such that when the securing nut 23 is screwed down on the electrode 15, this nut will serve to retain the shell 21 in position, it not being necessary to provide any great pressure on the shell 21 to retain it. Preferably, although not necessarily so, but particularly where the upper end of the porcelain 13 is not of a cylindrical shape, as indicated in Fig. 3, the space between the porcelain 13 and the shell 21 is filled with cement 24.

The shell 21 is made out of a resilient material, any of the synthetic resins being suitable. The essential characteristics of the materials used are resiliency, high dielectric strength, a sufficient rigidity to remain in place even when exposed to hot oil, operative temperatures of the engine, and the like. The shell 21 is formed in the nature of a petticoat-type insulator to increase the dielectric path from the upper end portion of the electrode 15 over the shell down to the body 10. In the present form, this increased dielectric path is secured by annularly recessing the upper portion of the shell 21 exteriorly thereof to provide a plurality of sharp lips 25, herein shown as four in number, the lower three of which have the shell sloping inwardly therefrom as indicated in Fig. 1.

Thus when the plug, assembled as above described, is to be installed, the hexagonal part 26 is engaged with the usual wrench. No other surface of the plug is provided to receive a wrench since the ferrule 17 is entirely concealed and cov-

ered over. Should the wrench slip off of the part 16 when the plug is being firmly seated, no damage will be done to the porcelain 18 should the wrench strike the shell 21. The porcelain, as is well known, is quite brittle and fractures readily under sharp impacts, particularly when applied laterally.

While I have herein shown and described my invention in the one particular form, it is obvious that structural changes may be employed without departing from the spirit of the invention and I, therefore, do not desire to be limited to that precise form beyond the limitations as may be imposed by the following claims.

I claim:

1. In combination with a spark plug having a porcelain insulator, an electrode extending therefrom, a metallic body surrounding a length of the porcelain, and means carried by the body to sealably retain the insulator with said body, 20 of a dielectric shell closely surrounding the exposed end of said insulator throughout its length and resting on said retaining means, a cement filling between said shell and said insulator increasing the dielectric gradient therebetween, and means engaging said electrode and said shell to draw the shell compressibly against said retaining means, said shell being formed out of material more resilient than said insulator where-

by positioning of said shell by said engaging means does not tend to shift said insulator relative to its retaining means.

2. Means for providing a large effective diameter of the extending end of the insulator in a two piece body spark plug of small diameter rating which consists of the combination of the small diameter body, an insulator having an enlarged intermediate portion for sealing engagement in the body, a metallic ferrule around the insulator above said portion, a separate insulating shell around the insulator above the ferrule, and a cement filling between the insulator and said shell, both the ferrule and the lower end of said shell being fitted to engage within the upper end of said body, said ferrule engaging said body to constitute the second and insulator retaining part of said body, said ferrule being screw-threadedly engaged with the body, and means for turning the ferrule covered by said shell, an electrode extending from the outer end of the insulator, and means engaging the electrode and said shell to center the shell on said insulator and further means engaging the electrode to retain the shell compressibly against said ferrule, said shell being made of more resilient material than that of the insulator.

PAUL G. ANDRES.
